4

FIGURE 1 is a side elevational view of the aerial tramway gondola showing my new design;

FIGURE 2 is a side elevational view of the aerial tramway gondola taken at 90° to FIGURE 1;

FIGURE 3 is a top view of the aerial tramway gondola; and

FIGURE 4 is a bottom view of the aerial tramway gondola.

Portions are shown broken away in FIGURES 1 and 2 to indicate indeterminate length.

I claim:

The ornamental design for an aerial tramway gondola, as shown and described.
